FIGURINE

Ruth A. Barone and Joseph Swbado, Toledo, Ohio

Application January 24, 1955, Serial No. 34,162

Term of patent 7 years

(Cl. D29—23)

The characteristic feature of the design is shown in full lines.

We claim:

The ornamental design for a figurine, as shown and described.
